UNITED STATES PATENT OFFICE.

WILLIAM H. FOX, OF MINNEAPOLIS, MINNESOTA, ASSIGNOR OF ONE-HALF TO BERNARD W. JAPS, OF MINNEAPOLIS, MINNESOTA.

DEMOUNTABLE RIM.

1,284,403.

Specification of Letters Patent.

Patented Nov. 19, 1918.

Application filed December 24, 1917. Serial No. 208,548.

To all whom it may concern:

Be it known that WILLIAM H. Fox, a citizen of the United States, residing at Minneapolis, in the county of Hennepin and State of Minnesota, have invented certain new and useful Improvements in Demountable Rims; and I do hereby declare the following to be a full, clear, and exact description of the invention, such as will enable others skilled in the art to which it appertains to make and use the same.

My invention relates to improvements in demountable wheel rims; and, to this end, it consists of the novel devices and combinations of devices hereinafter described and defined in the claims.

In the accompanying drawings, which illustrate the invention, like characters indicate like parts throughout the several views.

Referring to the drawings,

Figure 1 is a fragmentary view, partly in side elevation and partly in circumferential section, showing the invention applied to the felly of a wheel and holding a pneumatic tire.

Fig. 2 is a view in transverse section taken on the line 2-2 of Fig. 1;

Fig. 3 is an outside face view of a part 30 of the wheel rim that is spread out flat;

Fig. 4 is an outside face view of the demountable rim also spread out flat with some parts removed;

Fig. 5 is a view of the parts shown in Figs. 3 and 4 in assembled relation and locked together against circumferential movement;

Fig. 6 is a view corresponding to Fig. 5, with the exception that the removable tire-retaining flange of the demountable rim is shown in position;

Fig. 7 is a transverse section taken on the line 7-7 of Fig. 5, on an enlarged scale;

Fig. 8 is a transverse section taken on the line 8-8 of Fig. 6, on an enlarged scale;

Fig. 9 is a perspective view of the key;

Fig. 10 is a fragmentary perspective view looking at the inner face of the demountable wheel rim, with some parts removed;

Fig. 11 is a fragmentary perspective view looking at the outer face of the wheel rim;

Fig. 12 is a fragmentary perspective view of the detachable tire-retaining flange of the demountable rim; and

Fig. 13 is a modification, which takes the

place of the key shown in Fig. 9 for holding the two rims against a circumferential movement to unlock the same;

The numeral 14 indicates the felly of a wheel and the numeral 15 indicates the casing of a pneumatic tire, of the type having straight sides and secured to the felly by the invention. Rigidly secured to the felly 14, is a metallic wheel rim 16, having on one of its edges an integrally formed cam 65 flange 17 and on its other edge a multiplicity of circumferentially spaced cam lugs 18, that are beveled both circumferentially and transversely. Also integrally formed with the wheel rim 16, between two of the cam lugs 18, is a lug or abutment 19, the purpose of which will presently appear.

Removably secured to the wheel rim 16, by a circumferential and axial movement, is a demountable rim 20 having at its edges 75 tire-retaining flanges 21 and 22, the former of which is integral with said rim and the other of which is removable therefrom by a circumferential and axial movement. The flange 21 is integral with the edge of the demountable rim 20, which corresponds to the edge of the wheel rim 16 having the cam flange 17 and the flange 22 is detachably secured to the other edges thereof by a multiplicity of bayonet joints 24, the lugs of 85 which are integral with the flange 22 and the slots of which are cut in said rim. These bayonet joints 24 require first an axial movement and then a circumferential movement of the flange 22, with respect to the demountable rim 20, to interlock the two. Also formed in the tire-retaining flange 22, is a lock notch 25, the purpose of which will presently appear.

Integral with the inner face of the demountable rim 20, on the same edge portion thereof with the flange 21, is an annular cam flange 26 that is reversely beveled from the cam flange 17 on the wheel rim 16 for cooperation therewith. A multiplicity of 100 transverse passageways 27 is formed in the cam flange 26 for the cam lugs 18, to permit the demountable rim 20 to be moved axially onto or from the wheel rim 16. Also formed in the cam flange 26, is a transverse passage-way 28 for the lug 19. This lug 19 and passageway 28 correctly position the demountable wheel rim for application to or removal from the wheel rim 16.

An inwardly projecting flange 29, integral 110

with the inner face of the demountable rim 20, covers the adjacent joint between the two rims 16 and 20. This flange 29 is located laterally inward of the slots of the bayonet joints 24. Also integral with the inner face of the demountable rim 20, at the inner face of the flange 29, is a multiplicity of circumferentially spaced cam lugs 30 that are beveled, both circumferentially and transversely, for coöperation with the cam lugs 18. The engaging surfaces of the cam lugs 18 and 30 are reversely formed, so as to bear directly, the one upon the other.

In applying the demountable rim 20 to the wheel rim 16, the same is first given an axial movement to carry the cam lugs 18 through the passageway 27, the lug 19 through the passageway 28 and the cam flange 26 into engagement with the cam flange 17. Then a slight circumferential movement of the demountable rim 20, with respect to the wheel rim 16, will carry the cam lugs 30 into engagement with the cam lugs 18. The engaging cam flanges 17 and 26 and the cam lugs 18 and 30 place the two rims 16 and 20 under strain for reverse axial movement, thereby securely locking the same together and, at the same time, properly alining the demountable rim 20 on the wheel rim 16. These engaging cam flanges and cam lugs also truly center the demountable rim 20 on the wheel rim 16 and keep the same in true annular form.

To prevent a circumferential movement of the demountable rim 20 on the wheel rim 16 in a direction to release the engaging cam lugs 18 and 30, a key 31, in the form of a wedge, is mounted in a seat 32 formed in the flange 29 and adjacent edge of said rim 20 and inserted between the lug or abutment 19 on the wheel rim 16 and a lug or abutment 33 integral with the lug 30 adjacent to the seat 32. Obviously, these two circumferentially spaced abutments 19 and 33, the one on the demountable rim and the other on the wheel rim, engage opposite edges of the key 31 and thereby hold the two rims interlocked, to prevent a circumferential movement, which would release the engaging cam lugs 18 and 30. The key 31 is held in its seat 32 by a single nut-equipped bolt 34 passed through alined bores in the wheel rim 16 and an inwardly projecting lug 35 integral with the key 31. Integral with the key 31, is an outwardly projecting lock lug 36 arranged to enter the lock notch 25, when the tire-retaining flange 22 is interlocked with the demountable rim 20 by the bayonet joints 24, and thereby hold said flange against a circumferential movement to release the bayonet joints.

For the purpose of this case, it is not thought necessary to illustrate the valve stem, but it may be here stated that the necessary openings in the two rims and felly

will be provided and that the openings in the wheel rim and felly must be of sufficient size to permit the required circumferential movement of the demountable rim 20 on the wheel rim 16 to and from a locked position. 70

Referring to the modification, illustrated in Fig. 13, which takes the place of the key 31, shown in the remaining figures, the abutment 33 is beveled at 37 and a set screw 38, mounted in a fixed nut in the felly 14, impinges against the beveled surface 37 and circumferentially forces the cam lugs 30 onto the cam lugs 18, as shown. When this construction is used, additional means will, of course, have to be provided for locking 80 the removable retaining flange 22 in place.

What I claim is:—

1. The combination with a wheel rim, of a demountable rim therefor, said two rims having on one of their corresponding edges 85 coöperating cam flanges and on their other corresponding edges a plurality of circumferentially spaced, pairs of coöperating cam lugs, the cam flange on one of said rims having a plurality of circumferentially 90 spaced passageways for the cam lugs on the other of said rims to permit an axial movement of one of said rims to and from the other thereof, said cam flanges and lugs arranged to be interlocked by a circumferential movement of one of the rims with respect to the other to prevent axial separation thereof. 95

2. The combination with a wheel rim, of a demountable rim therefor, said two rims 100 having on one of their corresponding edges coöperating cam flanges and on their other corresponding edges a plurality of circumferentially spaced pairs of coöperating cam lugs, the cam flange on the demountable 105 wheel rim having a plurality of circumferentially spaced passageways for the cam lugs on the wheel rim to permit an axial movement of the demountable rim to and from the wheel rim, said cam flanges and lugs arranged to be interlocked by a circumferential movement of one of the rims with respect to the other to prevent axial separation thereof. 110

3. The combination with a wheel rim, of 115 a demountable rim therefor, said two rims having on one of their corresponding edges coöperating cam flanges and on their other corresponding edges a plurality of circumferentially spaced pairs of coöperating cam 120 lugs, the cam flange on the demountable wheel rim having a plurality of circumferentially spaced passageways for the cam lugs on the wheel rim to permit an axial movement of the demountable rim to and from 125 the wheel rim, said cam flanges and lugs arranged to be interlocked by a circumferential movement of one of the rims with respect to the other to prevent axial separation thereof, and a key for locking the two 130

10 rims against circumferential movement to release the coöperating cams.

4. The combination with a wheel rim, of a demountable rim therefor, said two rims having on one of their corresponding edges coöperating cam flanges and on their other corresponding edges a plurality of circumferentially spaced pairs of coöperating cam lugs, the cam flange on the demountable wheel rim having a plurality of circumferentially spaced passageways for the cam lugs on the wheel rim to permit an axial movement of the demountable rim to and from the wheel rim, said cam flanges and lugs arranged to be interlocked by a circumferential movement of one of the rims with respect to the other to prevent axial separation thereof, said pairs of coöperating cam lugs having engaging surfaces that are beveled both circumferentially and transversely of the wheel rim.
5. The combination with a wheel rim, of a demountable rim therefor, said two rims having on one of their corresponding edges coöperating cam flanges and on their other corresponding edges a plurality of circumferentially spaced, pairs of coöperating cam lugs, the cam flange on one of said rims having a plurality of circumferentially spaced 30 passageways for the cam lugs on the other

of said rims to permit an axial movement of one of said rims to and from the other thereof, said cam flanges and lugs arranged to be interlocked by a circumferential movement of one of the rims with respect to the other to prevent axial separation thereof, and a joint flange on one of the rims arranged to cover the circumferential joint between the two rims on the opposite side thereof from said passageways.

6. The combination with a wheel rim, of a demountable rim therefor, said two rims having coöperating cams for locking the same together by a compound axial and circumferential movement of the one with respect to the other, said demountable rim having at its edges tire retaining flanges one of which is removable by a compound circumferential and axial movement, and a key for locking said two rims and the removable tire retaining flange in assembled relation and against circumferential movement with respect to each other.

In testimony whereof I affix my signature in presence of two witnesses.

WILLIAM H. FOX.
